UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

CORRUGATED METALLIC WALL ELEMENT.

Application filed October 27, 1924. Serial No. 746,221.

The invention resides in forming corrugations or embossments in a metallic plate so as to increase its strength to resist exterior loads applied upon it. By forming 5 said corrugations or embossments integral with the plate, considerable fabrication of other parts and the necessity of riveting is eliminated, and the ultimate weight of the structure is retained at a minimum.

10 Such integrally reinforced plates are especially adaptable for end walls of railway freight cars where the shifting of the lading causes severe impacts against the end wall. These integral reinforcements also 15 resist the tendency of the plate to buckle, due to the torsional and weaving movements of the car in service.

Such a reinforced plate may also be used 20 for the side wall, floor, roof or door of a railway car.

It is immaterial how the corrugations are positioned in the plate or plates or how the corrugated plate or plates are positioned when on the car. The end wall of a railway 25 car is often broken, distorted or otherwise injured by the thrust caused by the inertia of the shifting of the cargoes when the car stops or starts. These thrusts may be local, tending to distort the end wall in some particular spot, as, for example, when a piece 30 of structural steel or other heavy lading shifts lengthwise and imparts a blow against the end wall of the car, or there may be a tendency to break out the whole 35 wall and tear it away from the car framing.

For the purpose, therefore, of greater strength, resiliency and durability, car walls have been constructed of steel plates or panels formed with integral ribs or corrugations.

40 One of the objects of my invention is to provide a corrugated metallic plate for use on railway cars in which the corrugations have a configuration and arrangement 45 that impart to the plate (or structure composed of several plates) a greater capacity for resisting the mechanical forces which tend to destroy it and also keep the weight at a minimum.

50 Such corrugations or embossments are mechanical beams and can be considered and calculated as such. When a car is

loaded with sand, grain, chats or other plastic material it imposes an equally distributed load upon these beams. An equally distributed load imposes a bending moment upon a beam which increases from the end to the middle of the beam, therefore, a beam must increase in strength correspondingly from its ends towards its middle. In my construction this is accomplished by gradually increasing the depth of the beam from its ends towards its middle.

Another object of my invention is to provide a comparatively wide corrugation so as 65 to obtain greater strength (by positioning more metal further away from the neutral axis) and at the same time arch or curve the apex or connecting member of the corrugations so as to transmit the loads to the 70 main walls without deflecting the apex or connecting member.

In my invention I maintain the arched construction and at the same time increase 75 the depth of the corrugation by reducing the radius of the arch or curve from the ends to the middle of the corrugation.

The increased depth of corrugation is obtained by increasing the height of the arched connecting member and not by increasing 80 the width of the main walls. The stretch in pressing is therefore not localized in the smaller wall portion of the corrugation but is (comparatively) distributed in the longer arched connecting portion of the corrugation. In pressing metallic plates where stretching is necessary, it is essential 85 to distribute such stretch over as large an area as possible to eliminate "thinned spots" or ruptures. In my design I maintain the 90 main walls at a constant width throughout the length of the corrugation with the exception, of course, of the terminal portions (14).

When a plurality of such corrugations is 95 used together it is immaterial whether they are in the same plate or in two plates secured together.

When a plurality of such corrugations is 100 used they are preferably parallel with each other.

In the drawings:

Fig. 1 shows my invention applied to a gondola type of railway freight car.

Fig. 2 is a section on line 2—2 of Fig. 1.
Fig. 3 is an enlarged section on line 3—3 of Fig. 1.

Fig. 4 is an enlarged section on line 4—4 of Fig. 1.

Fig. 5 is a section on line 2—2 of Fig. 1 showing a modification.

Fig. 6 is an enlarged section on line 3—3 of Fig. 1 showing a modification.

Fig. 7 is an enlarged section on line 4—4 of Fig. 1 showing the same modification as shown in Fig. 6.

Fig. 8 is a section on line 2—2 of Fig. 1 showing the same modification as shown in Fig. 6.

The corrugated plate 1 or plates may be secured to the car in any desired manner, the type selected for illustration being a gondola car with steel sides 2, angle iron end sill 3, striking casting 4, push pole pocket 5, etc., all of usual construction.

The integral reinforcing corrugation or rib comprises spaced apart main walls 6 which are preferably of constant width throughout the length of the corrugation and which are positioned obliquely to allow the plate to be easily withdrawn from the press. These main walls are connected by a curved portion 7, the radius 8 upon which it is formed decreasing from the ends towards the middle of the corrugation so as to increase the depth of the corrugation at or near its center. A series of such corrugations may be formed in a plate with flat portions 9 of the plate connecting such corrugations. See Figs. 3, 4 and 5.

If desired, a pair of such corrugations may be connected by an arched or curved portion 10 similar to the curved portion of the corrugation. In such a construction the curved portion connecting the corrugations could also have its radius 11 decreased from its ends to its middle. Such a construction is shown in Figs. 2, 6 and 7. The main wall is positioned midway between the plane 12 of the sheet and the apex 13 of the corrugations, as shown in Fig. 2. It may be desirable, however, to retain these main walls adjacent to the plane of the sheet and allow the portion connecting the corrugations to protrude slightly in the opposite direction from the corrugation. This latter construction is shown in Fig. 8.

I claim:

1. A metallic plate having a corrugation formed therein comprising spaced apart walls and a curved portion connecting said

walls, the radius of the curve decreasing from the ends to the middle of the corrugation so as to increase the depth of the corrugation. 60

2. A metallic plate having a corrugation formed therein comprising spaced apart walls and a curved portion connecting said walls, the radius of the curve decreasing 65 from the ends to the middle of the corrugation so as to increase the depth of the corrugation, the width of said walls remaining constant throughout the length of the corrugation. 70

3. A metallic plate having a plurality of corrugations formed therein comprising spaced apart walls, curved portions connecting said walls, and curved portions connecting said corrugations, the radius of the respective curves decreasing from the ends to 75 the middle of the corrugation, so as to increase the depth of the corrugation. 75

4. A metallic plate having a plurality of corrugations formed therein comprising spaced apart walls, curved portions connecting said walls, and curved portions connecting said corrugations, the radius of the respective curves decreasing from the ends to the middle of the corrugation, so as to increase the depth of the corrugations, the curved portions of the corrugations projecting oppositely from the curved portions connecting the corrugations. 80

5. A metallic plate having a plurality of corrugations formed therein comprising spaced apart walls, curved portions connecting said walls, and curved portions connecting said corrugations, the radius of the respective curves decreasing from the ends to the middle of the corrugations, so as to increase the depth of the corrugation, the width of the corrugations being substantially the same as the distance between the corrugations. 85 100

6. A metallic plate having a plurality of corrugations formed therein, the width of the corrugations being substantially the same as the distance between the corrugations, said corrugations comprising spaced apart walls, curved portions connecting said walls, and curved portions connecting said corrugations which project oppositely from the first mentioned curved portions, the radii of the respective curves decreasing from the ends to the middle of the corrugation, so as to increase the depth of the corrugation. 105 110
